UNITED STATES PATENT OFFICE

168,381

PAIR OF SPECTACLES OR THE LIKE

Elmer L. Schumacher, Southbridge, Mass., assignor to American Optical Company, Southbridge, Mass., a voluntary association of Massachusetts

Application August 13, 1952, Serial No. 21,034

Term of patent 14 years

(Cl. D57—1)

To all whom it may concern:

Be it known that I, Elmer L. Schumacher, a citizen of the United States of America, residing at Southbridge, in the county of Worcester and State of Massachusetts, have invented a new, original, and ornamental Design for a Pair of Spectacles or the like, of which the following is a specification, reference being made to the accompanying drawing, forming a part thereof.

Fig. 1 is a front elevational view of a pair of spectacles, showing my new design;

Fig. 2 is a top plan view of the pair of spectacles shown in Fig. 1 with the temples broken away for convenience of illustration; and

Fig. 3 is a side elevational view thereof.

The characteristic features of my design are shown in full lines in the drawing.

I claim:

The ornamental design for a pair of spectacles or the like, substantially as shown and described.
ELMER L. SCHUMACHER.
